(57) **CLAIM**

We claim the ornamental design for a heat shield for a gas turbine fuel nozzle, as shown and described.

DESCRIPTION

FIG. 1 is a perspective view of a heat shield for a gas turbine fuel nozzle embodying the invention.

FIG. 2 is a top view of the heat shield of FIG. 1.

FIG. 3 is a bottom view of the heat shield of FIG. 1.

FIG. 4 left side view of the heat shield of FIG. 1.

FIG. 5 side view of the heat shield of FIG. 1.

FIG. 6 is a rear view of the heat shield of FIG. 1; and, FIG. 7 is a front view of the heat shield of FIG. 1.

The elements shown in broken lines are included for the purpose of illustrating environment and form no part of the claimed design.
